[57] CLAIM

The ornamental design for a fused glass and plastic bow tie, as shown and described.

DESCRIPTION

FIG. 1 is the front perspective view of the bow tie;
FIG. 2 is the rear perspective view thereof;
FIG. 3 is the left side elevational view thereof; the side opposite being a mirror image of the side shown;
FIG. 4 is the rear elevational view thereof; and,
FIG. 5 is the bottom plan view thereof.

The broken lines showing the adjustable ribbon or strap are for illustrative purposes only and form no part of the claimed design.
